UNITED STATES PATENT OFFICE.

HIRAM V. ROWAN, OF JEANNETTE, PENNSYLVANIA, ASSIGNOR TO JEANNETTE TOY AND NOVELTY COMPANY, OF JEANNETTE, PENNSYLVANIA, A CORPORATION.

DESIGN FOR A GAME BOARD.

Application filed May 13, 1926. Serial No. 17,696. Term of patent 7 years.

To all whom it may concern:

Be it known that I, HIRAM V. ROWAN, a citizen of the United States of America, residing at Jeannette, in the county of Westmoreland and State of Pennsylvania, have invented a new, original, and ornamental Design for Game Board, of which the following is a specification, reference being had to the accompanying drawing, forming part thereof.

The figure is a view in plan of a game board, showing my new design, the same being a substantially flat and thin board.

I claim:

The ornamental design for a game board, as shown.

H. V. ROWAN.
